UNITED STATES PATENT OFFICE.

HOMER A. JONES, OF RUTHERFORD, NEW JERSEY.

DESIGN FOR A CIGAR-BAND.

43,283.

Specification for Design.

Patented Nov. 26, 1912.

Application filed September 21, 1912. Serial No. 721,722. Term of patent 3½ years.

To all whom it may concern.

Be it known that I, HOMER A. JONES, a citizen of the United States, residing at Rutherford, Bergen county, New Jersey, have invented a new, original, and ornamental Design for Cigar-Bands, of which the following is a specification, reference being had to the accompanying drawing, forming part hereof.

The figure is a face view of a cigar band, showing my new design.

I claim:

The ornamental design for a cigar band, as shown.

HOMER A. JONES.
